US00D943943S

(12) **United States Design Patent** (10) Patent No.: **US D943,943 S**
Lee (45) Date of Patent: **** Feb. 22, 2022**

(54) SHOE UPPER	2,578,681 A	12/1951	Everston
(71) Applicant: New Balance Athletics, Inc. , Boston, MA (US)	3,217,430 A	11/1965	Novick
(72) Inventor: Charlotte Lee , Manchester (GB)	4,249,321 A	2/1981	Nagy
(73) Assignee: New Balance Athletics, Inc. , Boston, MA (US)	D266,455 S	* 10/1982	Famolare, Jr. D2/969
(**) Term: 15 Years	4,578,882 A	4/1986	Talarico, II
(21) Appl. No.: 29/743,796	4,620,376 A	11/1986	Talarico, II
(22) Filed: Jul. 24, 2020	4,631,842 A	12/1986	Koskela
(51) LOC (13) Cl. 02-04	4,756,097 A	7/1988	Sanders
(52) U.S. Cl. USPC D2/972; D2/973	D299,183 S	* 1/1989	Brown D2/969
(58) Field of Classification Search	4,794,705 A	1/1989	Sanders
USPC .... D2/896, 900, 902, 904, 906-908, D2/916-924, 925-945, 969, 970-979; 36/1.5, 3 A, 83, 45, 99, 101, 112-116, 36/136	D301,385 S	* 6/1989	Weiner D2/908

(57) **CLAIM**

The ornamental design for a shoe upper, as shown and described.

DESCRIPTION

FIG. 1 is a lateral side view of the shoe upper;
 FIG. 2 is a top view thereof;
 FIG. 3 is a medial side view thereof;
 FIG. 4 is a front view thereof;
 FIG. 5 is a rear view thereof;
 FIG. 6 is a front perspective view from the lateral side thereof; and,
 FIG. 7 is a rear perspective view from the lateral side thereof.

The short, broken lines shown in the drawings illustrate portions of the shoe upper, including stitching, and environment that form no part of the claimed design.

1 Claim, 7 Drawing Sheets
